UNITED STATES PATENT OFFICE.

WILLIAM C. KENYON, OF ROCKFORD, ILLINOIS, ASSIGNOR TO THE ATWOOD VACUUM MACHINE COMPANY, A COPARTNERSHIP CONSISTING OF SETH B. ATWOOD AND JAMES T. ATWOOD, OF ROCKFORD, ILLINOIS.

METHOD OF MANUFACTURING COVERED-JOINT HINGES.

Application filed November 12, 1926. Serial No. 148,022.

This invention relates to covered joint hinges of the type especially designed for hanging automobile doors. These hinges comprise an outer and an inner hinge member having interfitting knuckles with the outer hinge member shaped to provide a covering portion adapted to cover and conceal the knuckle joint. The present invention has to do with hinges of this kind 5 manufactured from flat metal stock as distinguished from those cast or possibly forged to shape. My invention is, moreover, an improvement on that disclosed in my copending application, Serial No. 40,759, filed July 1, 1925.

The primary object of the present invention is to simplify and improve the method of manufacturing hinges of the character described, with the view to reducing the 10 cost of manufacture and to producing a superior hinge construction.

Other objects and attendant advantages will be appreciated by those skilled in this art as the invention becomes better understood by reference to the following description when considered in connection with the accompanying drawings in which—

Figure 1 is a sectional view illustrating the first operation of my improved method; 30 Figs. 2 and 3 are end and face views, respectively, of a blank after the first operation;

Fig. 4 shows the second operation;

Fig. 5 is a face view after the second 35 operation;

Fig. 6 shows the third operation;

Fig. 7 shows the blank in position for the 40 fourth operation;

Fig. 8 shows the completion of the fourth operation;

Fig. 9 shows the completion of the fifth 45 operation;

Fig. 10 is a section through the dies and blank shown in Fig. 9;

Fig. 11 is a perspective view of the dies used in the fifth operation and showing the blank inserted before starting this operation; 50 and

Figs. 12 and 13 are views of the inner face and end, respectively, of the hinge members assembled.

The covered joint hinge comprises an inner and an outer hinge member designated generally by 14 and 15, respectively, Figs.

12 and 13, each formed from flat metal 55 stock and having a knuckle portion which interfits with the knuckle of the other member and is held in operative relation therewith by means of a pintle pin 16. In this instance the inner hinge member has two 60 knuckles 17 and the outer hinge member three knuckles 18. This arrangement is not essential except as to certain phases of the invention and as specifically defined in certain of the claims. 65

The inner hinge member 14 may be manufactured by any suitable method such for example as disclosed in my copending application above mentioned, and the outer member 15 is manufactured in accordance with 70 the method which will now be described and which constitutes the subject matter of the present invention.

After a blank 19 has been cut to length from bar stock it is grooved on one face 75 only, preferably by means of one or more milling cutters depending on the number of knuckles, to partially shape the knuckles and provide clearance for the knuckle or knuckles of the complementary hinge member. In the example shown, two milling cutters in co-axial relation, designated by 21, are caused to feed lengthwise of the blank to mill grooves 22 extending from one end 23 to an intermediate point 24, these 85 grooves preferably having inclined side walls as shown to provide for displacement of metal when the grooved portion is being fashioned by bending or curling to form the knuckle proper. 90

The second operation consists in blanking out the material at the bottom of the grooves from the end 23 to the shoulders 27. This blanking or slotting is preferably done by a stamping or punching operation 95 employing a blanking die 20 as shown in Fig. 4. This operation leaves separate knuckle parts 25 which are continuations of the knuckle parts 26 formed by the grooving, and also leaves shoulders 27 at right 100 angles to the plane of the blank and providing abutment faces between the knuckle portions 26. As shown in Fig. 5, the shoulders 27 are inclined outwardly away from the end 23, that is, the slotted end of the 105 blank, for a purpose which will be described later in connection with the crowning operation.

The flat blank, grooved and slotted as described, is then placed on a die 28 with one end resting on a ledge 29 and is broken down at its slotted end by the action of a die 31, Fig. 6. The die 31 has an angular corner 32 which makes a corresponding depression 33 across the knuckle parts 25 and, by reason of the shape of this and the die 28, the said knuckle parts 25 will be turned laterally as shown by dotted lines in said figure.

This bending operation is the first of a series in forming the slotted and grooved end portion of the blank into a knuckle. 15 These operations, that is, for shaping or fashioning the knuckle, may be performed in any suitable or preferred manner and in this and in my copending application above mentioned they have been referred to as 20 bending or curling operations. After an initial bending operation the laterally turned end is placed in a die such as 34, Fig. 7, and pressure is applied either endwise on the blank or against the die to force the laterally turned end into the said die to curl or roll 25 said end into the knuckle as shown in Fig. 8. In my previous application the parts shown in Fig. 7 were inverted so that the part 35 acting against the end of the blank 30 offset from the slotted end became the pressure applying die, whereas in the present instance the die 34 moves in the pressure applying stroke and the flat end of the blank is rigidly clamped to the stationary die part 35. It is immaterial, however, whether the 35 die 34 is stationary or movable, since the bending, curling or rolling operation may be performed equally well in either way.

Following the formation of the knuckle 40 the blank is clamped in a holding die 36, Fig. 9, having a bottom die part 37 and is subjected to the action of a die 38 which bends the knuckle end of the blank laterally to the offset position shown in said figure. The 45 dies 37 and 38 are shaped as shown in Figs. 10 and 11, to perform additional operations, namely crowning the covering portion of the knuckle, broaching the sides of the knuckle parts and aligning the knuckles. To this 50 end the lower die 37 is shaped to provide broaching cutters 39 which enter between the knuckle parts and broach the sides thereof and at the same time enter into the operation 55 of aligning the knuckles. The curved knuckle parts 25 will be pressed against the circular seats 41 and the end portions 42 of the knuckle will be subjected to the action of the top die 38 which is shaped to crown the knuckle, as shown in Fig. 12. This 60 crowning operation is effected by displacement of the metal to conform to the shape of the dies and as a result of such displacement the inclined shoulders 27 will be brought into parallel or coplanar relation as 65 shown in Fig. 12. At the same time the

knuckles being confined on all sides by die faces they will be accurately aligned. The pivot pin hole will be bored, it being noted that the depression 33 is so located as to lead the boring tool laterally away from the 70 cover side of the knuckle so that the hole will be slightly eccentric with respect to the cover portion, thus gaining a certain degree of clearance between the periphery of the complementary knuckle and the internal wall 75 of the cover portion.

As the result of the foregoing method of manufacture the number of operations is reduced, it being particularly noted that there is but a single milling operation, namely, that of milling the grooves. The slot blanking operation is especially simple and at the same time provides the shoulders 27 which serve as stops adapted to abut against the inner hinge member 14 for limiting the 80 opening of the hinge. The depression 33 is formed simultaneously with the first bending or break down operation. Following the formation of the knuckle proper in the 85 fourth operation shown in Fig. 8, the knuckle is turned or rolled laterally, crowned, broached and aligned in a single 90 set of dies. It may be said, therefore, that the operations of laterally offsetting the knuckle, crowning, broaching and aligning 95 are performed simultaneously.

It is believed that the advantages of my improved method will be apparent from the foregoing, although it should be understood that my invention is not confined to the details and specific operations described, since in practice these may be changed and modified within the spirit and scope of the invention as expressed in the appended claims.

I claim:

1. The method of manufacturing a covered joint hinge member from a flat metal blank, consisting in grooving one side only of the blank, said grooving extending longitudinally from one end and terminating at an intermediate point, slotting through the bottom of the grooving adjacent to said end, bending said slotted end laterally, and bending or curling said end and grooved portion to form a covered joint knuckle. 105

2. The method of manufacturing a covered joint hinge member from a flat metal blank, consisting in grooving one side only of the blank, said grooving extending longitudinally from one end and terminating at an 110 intermediate point, slotting through the bottom of the grooving at said end by a punching or blanking operation, said slotting leaving separated knuckle parts extending from the grooved knuckle portion which is adapted to provide a covering for the knuckle joint, and subsequently bending or curling the said knuckle parts and grooved portion to provide a covered joint knuckle 115 having said separated knuckle parts at an 120

open side and said grooved covering portion at the opposite side.

3. The method of manufacturing a covered joint hinge member from a flat metal blank, consisting in milling two parallel grooves in one side only of the blank, said grooving extending longitudinally from one end to an intermediate point, slotting through the bottom of said grooves 10 from said end to a point intermediate the ends of the grooves, thereby forming a shoulder at the open end of each groove, said shoulders being inclined from the center outwardly away from the end face above mentioned, bending or curling the grooved and slotted portions to form a covered joint knuckle, and crowning the covering portion 15 of the knuckle by a stamping operation which by displacement of metal brings said inclined shoulders substantially into co-planar relation.

4. The method of manufacturing a covered joint hinge member from a flat metal blank, consisting in grooving one side 25 only of the blank to provide spaced knuckle parts and a cover portion, bending or curling said grooved end portion of the blank into a knuckle, and simultaneously offsetting said knuckle from the plane of the blank 30 body, crowning the cover portion of the knuckle, and aligning the knuckle parts.

5. The method of manufacturing a covered joint hinge member from a flat metal blank, consisting in grooving one side 35 only of the blank, said grooving extending longitudinally from one end and terminating at an intermediate point, slotting through the bottom of the grooving adjacent to said end, said slotting leaving separate knuckle parts and a shoulder at the outer end of the grooving, bending said knuckle parts laterally and simultaneously forming 40 to said end, said slotting leaving separate knuckle parts and a shoulder at the outer end of the grooving, bending said knuckle parts laterally and simultaneously forming

an angular depression at the bend, and further bending or curling said knuckle parts and the adjacent grooved portion to form 45 a covered joint knuckle proper.

6. The method of manufacturing a covered joint hinge member from a flat metal blank including grooving one side only of the blank, said grooving extending longitudinally from one end and terminating at an intermediate point, slotting through the bottom of the grooving at said end by a punching or blanking operation, said slotting leaving separated knuckle parts extending 50 from the grooved knuckle portion which is adapted to provide a covering for the knuckle joint, and fashioning said slotted and grooved portions to provide a covered joint knuckle.

7. The method of manufacturing a covered joint hinge member from a flat metal blank, consisting in grooving one side only of the blank, said grooving extending longitudinally from one end to an intermediate point, slotting through the bottom of the grooving adjacent to said end, said slotting leaving separated knuckle parts and a shoulder at the outer end of the grooving, bending said knuckle parts laterally 65 and simultaneously forming an angular depression at the bend, further bending or curling said knuckle parts and the adjacent groove portion to form the knuckle proper, laterally offsetting the knuckle from the 70 plane of the blank by a final bending operation, and simultaneously with said final bending operation crowning the cover portion of the knuckle and aligning the 75 knuckles.

In witness of the foregoing I affix my signature.

WILLIAM C. KENYON.
